UNITED STATES PATENT OFFICE.

PHILIP HOGAN, OF ST. LOUIS, MISSOURI.

SEAM ANCHOR.

Application filed May 23, 1924. Serial No. 715,290.

To all whom it may concern:

Be it known that I, PHILIP HOGAN, a citizen of the United States, residing at St. Louis, Missouri, have invented a certain new and useful Improvement in Seam Anchors, of which the following is a specification, such as will enable others skilled in the art to which it appertains to make and use the same.

10 My invention relates to seam anchors for attaching cables, pipes, and other devices to a wall.

In Patent No. 1,474,835, issued to me November 20, 1923, I disclose a seam anchor comprising members adapted to be drawn toward each other to force portions inserted in the seam against the opposite walls of the seam.

20 The object of my present invention is to secure similar results by inserting a bearing member between a pivotal member and the face of the seam toward which the member naturally tends to move, thereby eliminating an element of the seam anchor present in 25 the above-mentioned patent.

In the accompanying drawings illustrating my invention—

Figure 1 is a section through a portion of a wall showing a seam and one member 30 of my anchor inserted therein in its initial position.

Figure 2 is an isometric view of the other element of the anchor.

Figure 3 is a section corresponding to 35 Figure 1 but showing the seam anchor elements assembled and in place in the seam.

Figure 4 is a transverse vertical section on line 4—4 of Figure 3.

Figure 5 illustrates a modification of my 40 invention.

In the drawings A and B indicate two bricks separated by a layer of mortar C, a portion of which is removed at intervals to form seam D. 1 is a bar having a portion 2 extending at an angle to the body portion and adapted to be easily inserted into the seam when the bar is turned as shown in Figure 1 in which the exterior angle formed by the bar forms a fulcrum 3 engaging the lower face of the seam and about which the bar may be turned as a pivot until the end 4 of portion 2 engages the upper face of the seam, as indicated by the full lines in Figure 1.

55 The bar may then be distorted into the position indicated by the dot and dash lines in

Figure 1 and it will be understood that the bar will be of material possessing sufficient elasticity to tend to return to the full line position. It is prevented from returning 60 to such position and its fulcrum 3 and end 4 are frictionally held in engagement with opposing faces of the seam by means of a bearing block 5 preferably recessed as indicated at 6 to receive the bar and the thickness of which above its recess corresponds to the distance from the upper face of body 1 to the upper face of the seam. With this block inserted as indicated in Figure 3, it will be clear that block 5, bar fulcrum 3 and 70 end 4 form three spaced points of application of pressure to the seam surfaces which resist withdrawal of the bar from the seam.

The recess 6 in block 5 is provided for 75 the purpose of engaging the sides of bar 1 so as to prevent relative movement of the bar and block transversely of the bar. The block is preferably provided with depending lugs 7 at its forward end adapted to 80 engage the front face 8 of the wall to prevent movement of the block inwardly of the seam or longitudinally of the seam.

Obviously, various modifications in the 85 details of the structure may be made and in Figure 5 I illustrate a modification in which the front of the block 9 is provided with an enclosed slot 10 for the passage of the bar.

In Figure 3 I show an insulator 12 carried on bar 1 by means of a bolt 13, but it will be understood that other means for supporting a line or the like upon the bar may be provided as may be desired.

I claim:

1. A seam anchor comprising a bar having a portion extending at an angle to the body of the bar, and a block approximating in thickness the width of the seam less the thickness of the bar.

2. A seam anchor comprising a bar having a portion extending at an angle to the body of the bar and adapted to be inserted into a wall seam with its end engaging one seam face, with the exterior of its angle 105 engaging the opposite seam face and with the body of the bar extending diagonally away from said latter face, and a bearing block to be inserted between the bar body and said first-mentioned seam face.

3. A seam anchor comprising a bar having a portion extending at an angle to the

95

105

110

body of the bar and adapted to be inserted into a wall seam with its end engaging one seam face, with the exterior of its angle engaging the opposite seam face and with the 5 body of the bar extending diagonally away from said latter face, a bearing block to be inserted between the bar body and said first-mentioned seam face, and a flange on said block for engaging the exterior face of 10 the wall when the element is so inserted.

4. In a seam anchor, a bar adapted to be inserted in a wall seam and upon distortion lengthwise to engage opposite faces of the seam, a bearing block adapted to be 15 inserted in said seam between said bar and one of the seam faces and frictionally retained to hold said bar in distorted position, and a flange on said block for engaging the outer face of said wall.

20 5. In a seam anchor, a bar adapted to be inserted in a wall seam and upon distortion transversely of its length to engage opposite faces of the seam, a bearing block adapted to be inserted in said seam between said 25 bar and one of the seam faces and frictionally retained to hold said bar in distorted position, and a flange on said block for engaging the outer face of said wall, said flange being provided with an enclosed slot 30 surrounding said bar.

6. In an anchor to be mounted in a wall seam, an angular member adapted to extend inwardly of the wall seam and adapted

to be pivoted about its exterior angle which engages a seam face and in a plane normal 35 to the seam, and an element engaging said member and the wall so as to prevent pivotal movement of said member in the plane of the wall seam.

7. In an anchor to be mounted in a wall 40 seam, an angular member adapted to extend inwardly of the wall seam and adapted to be pivoted about its exterior angle on a seam face and in a plane normal to the seam, and an element having a flange forming a seam bearing for said member, having surfaces engaging surfaces of said member at right angles to the seam engaging surfaces of said member, and having a flange 45 extending at right angles to said bearing flange.

8. In a seam anchor, a bar adapted to be inserted in a wall seam and upon distortion transversely of its length to engage opposite faces of the seam, a bearing block adapted to be inserted in said seam between said bar and one of the seam faces and frictionally retained to hold said bar in distorted position, the bar engaging face of 55 said block having a channel-shaped recess, the sides of which engage the edges of said bar.

In testimony whereof I hereunto affix my signature this 12th day of May, 1924.

PHILIP HOGAN.
